FOUNDATION

Abraham Louis Finkelstein, New York, N. Y., assignor to Snug-Fit Foundations, Inc., New York, N. Y., a corporation of New York

Application January 29, 1938, Serial No. 187,585

9 Claims. (Cl. 2-27)

This invention relates to structurally improved foundation or corset primarily intended for feminine wear.

It is an object of the invention to provide an article of this character which will efficiently mold, confine and support the various portions of the body so that the wearer may appear to the best advantage.

It is a further object of the invention to achieve the desired results without the slightest discomfort to the wearer.

It is a still further object to construct a garment of this character which will support the abdominal portions of the body in an extremely desirable manner and so that such portions will have a substantially flat or non-bulging appearance. This, however, will be achieved without in any substantial sense confining the movements of or otherwise discomforting the wearer.

An additional object is that of furnishing a garment of this type which may, without difficulty, be manufactured by those skilled in the art, and which garment may moreover be produced at relatively nominal cost and will serve the needs of the wearer for long periods of time without need of repair or replacement.

With these and other objects in mind, reference is had to the attached sheet of drawings illustrating one practical embodiment of the invention, and in which:

Fig. 1 is a front view of a foundation or corset;

Fig. 2 is an inner face view of the front assembly of such garment and with the latter in opened condition;

Fig. 3 is an enlarged sectional view taken along the lines 3-3 and in the direction of the arrows as indicated in Fig. 2;

Fig. 4 is an enlarged sectional side view taken along the lines 4-4 and in the direction of the arrows as indicated in Fig. 2; and

Fig. 5 is a transverse sectional view taken along the lines 5-5 and in the direction of the arrows as indicated in Fig. 2.

It will primarily be understood that the main portions of a garment embodying the teachings of the present invention may be formed of any desirable material cut according to any required style and color and otherwise formed to correspond to the dictates of the then current mode.

With this thought in mind, it will be observed, as shown in Figs. 1 and 2, that the numeral 10 indicates a front panel preferably formed of inelastic material having a preferably triangular inset 11 of material which should be at least elastic in its transverse direction. This front

panel has disposed adjacent each of its side edges, strips 12 of material which again are transversely or circumferentially elastic. Beyond the strips 12, side panels 13, of material similar to that of panel 10, may be disposed. To the rear of panels 13, further strips 14, of resilient material, may be disposed. These strips, as shown, may have their upper edges extending tangentially and in a plane below that of the upper edges of strips 12. At points above the upper edges of strips 14, and secured to such edges, inserts 15 may be provided, which bridge the space existing between side panels 13 and the back panel 16. The rear edges of strips 14 are, of course, secured to this back panel, and the latter may have, for example, tubular or receiving portions 17, which receive reinforcing strips (not shown).

A garment of this character should have a line along which it may be opened. Preferably, and as shown, one of the side panels 13 is split and the edges therof may be reinforced as indicated at 18 and mount a series of fastening elements 19. While these elements have been shown in the form of hooks, it is obvious that any other suitable form of fastening element might be employed.

Also, as indicated, each of the strips 11, 12 and 14 may incorporate self edging and, additionally, the back panel 16 may, if desired, be reinforced along its lower edge.

Adjacent the top edges of panel 10, strips 12, panels 13, and bust-supporting portions 20 may be provided, and which will function as a brassière of any desired type. As indicated at 21, the central portion of panel 10 may be extended upwardly to form an integral part of this brassière portion. Moreover, shoulder straps 22 may have their forward ends attached to portion 20 and their rear portions secured to the back panel 16, it being, further, noted that side garters 23 may be coupled to the side panels 13 adjacent their rear edges.

Now with a view to furnishing a structure which will properly support and confine the abdomen and which will, moreover, function to maintain the entire garment in proper condition, attention is invited especially to Figs. 2 and 3. In these views, it will be observed that the front panel 10, strips 12, and side panels 13, have underlying them an assembly comprising side strips 24, which may have their upper edges secured to the upper edges of front panel 10. The side edges or strips of panels 24 are secured to side panels 13 substantially adjacent the center there-

of, and at this point the panels 24 are enlarged either integrally or by a separate strip 25 as shown, to preferably extend from the top edge of panel 10 through to the lower edge of the same. In this connection, it will be noted that the main portions of panels 24 terminate in downwardly inclined edges and are interrupted at a point well above the lower edges of panel 10. Panels 24 are connected to each other by means of an interposed resilient strip 26. While the upper edges of panels 24 are connected by stitching or otherwise to panel 10. The upper edge of strip 26 should be free, and this strip should additionally present a socket or tubular portion within which is disposed a reinforcing element 27. It will likewise be apparent that strip 26 is flared downwardly and terminates substantially in line with the upper edge of the resilient portion 11, the lower ends of panels 24 extending in line with the lower ends of panel 10. Additionally, panels 24 may be formed with transverse lines of reinforcing, as indicated at 28; these extending preferably tangentially and being interrupted by sheaths or pockets, receiving reinforcing elements 29 of a length substantially equal to that of element 27. In this manner, it will be apparent that the assembly underlying front panel 10, elastic strips 12, and part of the side panels 13, will present an extremely flexible and confining structure such that the abdominal wall will be supported.

Finally, it will be noted that with a view to properly supporting the front garters 30, that these are preferably affixed to loops which ride along strap portions 31. The inner ends of the latter are secured to the lower edges of panels 24, while their outer ends are secured to the lower edges of panel 10. Accordingly, and regardless of the peculiarity of the build of the wearer, the garters 30 will at all times adjust themselves to where such wearer will enjoy a maximum of comfort and the stockings will at all times receive proper support.

Thus, among others, the several objects of the invention as specifically afore noted are achieved. Obviously, numerous changes in construction and rearrangement of the parts might be resorted to without in any sense departing from the spirit of the invention as defined by the claims.

Having thus described the invention, what is claimed is:

1. A corset including a front section of substantially the width of the front of the body having an interior portion and an exterior portion, said interior portion comprising a central vertical panel of a material elastic in a horizontal direction and having a pair of lateral panels attached thereto at each side, non-elastic in a horizontal direction and said exterior portion having a central non-elastic panel and a pair of lateral panels attached thereto of a material elastic in a horizontal direction and a body encircling means attached to both of said portions of said front section.

2. A device in accordance with claim 1 in which each of said elastic panels is of less width than the corresponding non-elastic panel of the other portion of said front section.

3. A device in accordance with claim 1 in which the panels of each portion are connected by seams and the panels are of such width that the seams of each portion engage a non-elastic panel of the other portion.

4. A device in accordance with claim 1 having breast supporting pockets attached to the upper portion of the central panel of the outer portion of the front section and attached to the body encircling means and said breast pockets being attached to the upper end of the lateral panels of the interior portion.

5. A device in accordance with claim 1 in which the central panel of said inner portion is provided with vertical reinforcing strips extending from the level of the hipline to the level of the bottom of the breast pockets.

6. A device in accordance with claim 1 in which the lateral panels of the interior portion of the front section are provided with vertical reinforcing strips extending from the level of the hipline to the level of the bottom of the breast pockets said reinforcing strips being situated close to the lateral edges of the central elastic panel of the interior portion.

7. A device in accordance with claim 1 in which the central panel and the lateral panels of the inner portion are provided with vertical reinforcing strips extending from the level of the hipline to the level of the bottom of the breast pockets said reinforcing strips being situated close to the lateral edges of the central elastic panel of the interior portion.

8. A device according to claim 1 in which the lateral panels of the interior portion of the front sections are provided with vertical reinforcing strips extending from the level of the hipline to the level of the bottom of the breast pockets and provided with laterally extending reinforcing strips within said lateral panels of the interior portion having their ends overlapping said vertical reinforcing strips.

9. A device in accordance with claim 1 having breast supporting pockets attached to the upper portion of the central panel of the outer portion of the front section and attached to the body encircling means, the edges of the upper end of the lateral panels of the interior portions, which edges are adjacent to the central panel, being attached to the said breast pockets and the remainder of the upper end of the lateral panels being free from the breast pockets and the upper end of the attachment of the lateral panels to the body encircling member being spaced from the breast pockets to permit elasticity at the lower line of the breast pockets.

ABRAHAM LOUIS FINKELSTEIN.
